UNITED STATES PATENT OFFICE

131,141

DESIGN FOR AN HYDRAULIC TESTING MACHINE

Tinius Olsen, 2nd, Philadelphia, Pa.

Application December 7, 1940, Serial No. 97,146

Term of patent 7 years

To all whom it may concern:

Be it known that I, Tinius Olsen, 2nd, a citizen of the United States, residing at Philadelphia, in the county of Philadelphia and State of Pennsylvania, have invented a new, original, and ornamental Design for an Hydraulic Testing Machine, of which the following is a specification, reference being had to the accompanying drawing, forming a part thereof.

The figure is a perspective view of an hydraulic testing machine, showing my new design.

The rear of the testing machine casing is open, while the right hand end or side portion is plain.

The front and rear of the cross head unit is substantially similar except for the omission of the crank member from the rear thereof.

I claim:

The ornamental design for an hydraulic testing machine, substantially as shown and described.

TINIUS OLSEN, 2ND.
